UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

DOOR-GUARD.

1,287,717.

Specification of Letters Patent. Patented Dec. 17, 1918.

Application filed July 20, 1914. Serial No. 351,905.

To all whom it may concern:

Be it known that I, JAMES F. McELROY, a citizen of the United States, residing at Albany, county of Albany, State of New York, have invented certain new and useful Improvements in Door-Guards, the following being a full, clear, and exact disclosure of the one form of my invention which I at present deem preferable.

For a detailed description of the present form of my invention, reference may be had to the following specification and to the accompanying drawings, which illustrate my invention, wherein,

Figure 1 shows my apparatus in a diagrammatic form,

Fig. 2 is a section of the yielding guard or fender, Figs. 3 and 4 show details of the disabling and non-interference features.

My invention relates to safety devices for protecting persons and objects in the doorway of a motor-operated door. It has been heretofore proposed to provide a motor-propelled device, such as a door or vehicle, with a guard or fender, which, upon encountering an obstacle in its path, will yield and thereby bring into action arresting-devices for the door or vehicle. In the present case I propose to employ with a door such a yieldable guard or fender (hereinafter referred to as a guard) which is preferably mounted on the door itself and which on encountering an obstacle not only causes the arrest but also the backward movement of the door toward its open position. For that purpose the yielding guard exercises control over the door-motor, preferably by electrical devices, comprising contacts which are operated by the yielding of the guard and which serve to dominate a control-circuit for the motor.

The motor is preferably a pneumatic one having an electromagnetic controller located in the aforesaid control-circuit. The said control-circuit also contains doorman's contacts by which the doorman may both open and close the door, whereas the guard-contacts only dominate the door-opening function of said circuit. In addition, I provide that the door-opening function of the guard-contacts shall be disabled or suspended when the door is closed, so that the guard cannot be used at that time for unauthorized opening of the door. I furthermore provide non-interfering devices for preventing interference between the door-opening function of

the guard-contacts and the door-closing function of the doorman's contacts.

In the drawing, A represents a door, and A¹ a yielding guard mounted on the forward edge thereof. The details of the guard are shown in Fig. 2. It is in the form of a channel A¹ having about the same width and length as the door itself and telescoping over a similar and parallel guide-channel A² secured to the forward edge of the door A. Supporting links a are jointed, near their lower ends, to A² at points a¹, and to A¹ at points a², the extreme lower end of each link projecting beyond the pivotal point a¹ and bearing on A² to afford a stop for the outward play of the guard A¹. The guard A¹ is normally pressed outward away from the door by springs A³, A³ each of which is mounted on a hollow stud secured to A² and bears at its outer end against A¹. On guide-channel A² are mounted two insulating blocks b, b, each carrying a set of contacts B. These contacts are in the form of springs which normally stand apart from and out of contact with each other, but lie in the path of an insulating block b¹ on guard A¹. Hence when the guard A¹ yields, upon coming in contact with a person in the doorway or other obstacle, it will cause one or both sets of contacts B to come together and close, at that point, the circuit to which they are located, the two sets of contacts being in multiple in the circuit, as shown in Fig. 1. While I have shown two sets of contacts, it is obvious that but one set, or more than two sets might be employed. From the guard-contacts B, B, the circuit wires 1 and 2 extend, within the door to contact-fingers C¹ and C², the former being split, which, as the door travels, slide upon stationary strips D¹ and D² respectively. By this means the to-and-fro movement of the door still permits the maintenance of electrical communication with the guard-contacts, although, as will be more fully explained hereinafter, such communication is broken when the door is closed, the fingers C¹ and C² then passing off from the ends of the strips D¹ and D², in order to deprive the guard-contacts of their normal domination of the motor-controlling circuit. This closed position of the door is illustrated in Fig. 1, also in Figs. 3 and 4. Moreover, when the door is fully opened, finger C¹ will pass off from strip D¹ and come upon two short strips f¹, f² in the door-clos-

ing side of the motor-controlling circuit, as will be hereinafter explained.

The pneumatic door-motor is indicated at G and the electromagnetic controller therefor at H. The motor and its controller may be of any desired kind wherein the motor valves are worked by electromagnets. It is sufficient for this case to merely indicate them, it being understood that the door-opening magnet is contained in the left-hand part h^1 of the controller casing and the door-closing magnet in the right-hand part h^2 . The doorman's contacts are shown at E and F, being merely two push buttons of which E serves to close the door-opening magnet and F the door-closing magnet of the controller. When the doorman, by pushing the button, closes the door-opening contacts at E, the circuit will be from the battery or source of current K, by wire 3, through the door-opening magnet at h^1 , to ground. When he closes the door-closing contacts at F, the circuit will be from the battery or source of current K, by wire 4 (assuming that the short strips f^2 and f^1 are connected by finger C^1 , the door being open) to the door-closing magnet at h^2 , and thence to ground. The latter circuit can be established only when the door is fully open and will be broken by movement of fingers C^1 from contacts f^2 and f^1 , after the door starts to close. The closing movement of the door which has been thus initiated will be continued, however, since the door closing valves of the motor have been set by the magnet at h^2 and will remain set until reversed by the action of the opposing door-opening magnet at h^1 . By this expedient the doorman loses control of the door-closing operation after the door has once started on its closing run, and he therefore can not interfere, by continuing to press on his door-closing button, with the automatic reversal of the door movement by the guard contacts B. That automatic reversal will occur in the event of the door encountering on its closing run, a person in the doorway or other obstacle which will cause the guard A to yield, against the outward pressure of springs A^3 , and close guard contacts B. When guard-contacts B close, they establish a separate branch of the door-opening side of the control-circuit by way of the wire 3^a , which branch includes, as a loop therefrom, the stationary strips D^1 , D^2 and the guard-contacts B, the latter communicating with said strips respectively by the fingers C^1 and C^2 . The route of the current in this emergency, when the door-opening side of the motor-controlling circuit is thus closed by the guard-contacts, is indicated in Fig. 1 by the double arrow-heads on the circuit wires 1, 2, and 3^a . If, however, the door is fully closed, that emergency route can not be established, because the fingers C^1 and C^2

are then out of contact with strips D^1 , D^2 . The result is that, when the door is closed, the guard-contacts are disabled, or deprived of their function of acting upon the door-opening side of the motor-controlling current to cause the door to open. If it were not for such disability, it would be possible for a passenger to pry the guard in, by means of the fingers or a knife-blade, and cause it to open the door by closing the aforesaid emergency circuit. To prevent such unauthorized opening of the door is the purpose and effect of my device. The door may still be opened in the normal and authorized way by pressing the doorman's contacts E.

What I claim as new and desire to secure by Letters Patent is:

1. The combination with a door, of a guard yieldably supported thereby, a motor for operating the door, an electromagnetic device controlling the said motor, means coöperating with said guard to render said electromagnetic device operative to effect reversal of the motor upon movement of the guard independently of the door, and means for disabling the controlling function of said guard when the door is shut.

2. The combination with a door, of a guard yieldably supported thereby, a motor for operating the door, the movement of said motor in one direction being controlled by said guard, a doorman's control for said motor, and means for rendering the doorman's control inoperative to prevent its interference with the functions of said guard.

3. The combination with a door, and a motor for operating the same, of an electromagnetic device for controlling said motor, a guard movably attached to said door, a doorman's circuit for controlling said electromagnetic device, a branch circuit shunting a portion of said electromagnetic device, normally separated contacts in said branch circuit controlled by movement of said guard, and means for rendering the doorman's control inoperative to prevent its interference with the functions of said guard.

4. The combination with a door, and a motor for operating the same, of an electromagnetic device for controlling said motor, a guard movably attached to said door, a circuit for said electromagnetic device, a branch circuit controlled by said guard and shunting a portion of said electromagnetic device, and means independent of the guard for breaking said branch circuit when the door reaches a predetermined position.

5. The combination with a door, of a yielding guard, a door motor, a motor controller, electric circuits for said controller, doorman's contacts for said circuits, a branch circuit shunting the doorman's contacts and a portion of said motor controller, guard contacts operated by movement of

- said guard and controlling said branch circuit, and means for rendering the doorman's control inoperative to prevent its interference with the functions of said guard.
- 5 6. The combination with a door, of a yielding guard mounted thereon, electric contacts carried by said door and positioned to be operated by said guard, means for maintaining electrical connection with said contacts as the door moves, a motor for said door and an electromagnetic controller for said motor, main circuits for said controller, and a branch circuit controlled by said contacts for shunting one of said main circuits.
- 10 7. The combination with a door, of a yielding guard thereon, contacts on the door and positioned to be operated by said guard, means for maintaining electrical connection with said contacts as the door moves, a motor for said door, an electromagnetic controller for said motor, main circuits for said controller, and a branch circuit controlled by said contacts for shunting one of said main circuits and doorman's contacts in circuit 20 with said controller and said branch circuit.
- 25 8. The combination with a door, of a yielding guard therefor, contacts on the door operated by the guard, a pneumatic door-motor, an electromagnetic controller for said motor, doorman's controlling circuits and contacts 30 dominating the controller, a branch circuit shunting the doorman's controlling contacts and a portion of said controller and dominated by said guard actuated contacts, doorman's contacts dominating the controller, and means for disabling the guard contacts 35 by the movement of the door.
9. The combination with a door, of a yielding guard mounted on the door, contacts on the door operated by said guard, a door-motor, a branch circuit extending to said contacts and controlling movement of the motor in one direction, and sliding contacts for maintaining connection with the door as it moves, said sliding contacts having their connection broken when the door is closed.
- 40 10. The combination with a door, of a yielding guard therefor, contacts carried by the door and positioned to be operated by said guard, a door-motor, doorman's contacts, a door-opening circuit for the motor controlled by both the guard-contacts and a doorman's contact, a door-closing circuit for 45 said motor controlled by another of the doorman's contacts, and means for preventing interference between the door-opening control of the guard-contacts and the door-closing control of the doorman's contacts.
- 50 11. A yieldable guard for doors comprising a guide member, a guard member telescoping therewith to form a chamber, arms

pivotally attached to said guide member and said guard member to hold them in movable relation, said arms having fingers to limit pivotal movement thereof, means within the 65 chamber for yieldingly pressing said guard member outwardly, and door operating means controlled by said guard member.

12. The combination with a door, a motor for opening and closing the door, an electromagnetic controller for said motor, a doorman's door opening circuit connected with said controller, a doorman's door closing circuit connected with the controller, a yielding guard mounted on the door, contacts on the 70 door operated by the movement of said guard, a doorman's controller for opening and closing said circuits, a branch door-opening circuit shunting the doorman's controller and extended to said contacts, and 75 sliding contacts in said branch circuit for maintaining electric connection with the door during its opening and closing movements, the doorman's closing circuit being adapted to be bridged by said sliding contact means on the door when the latter is in its open position, and to be broken when the door has moved to its closing position, whereby the doorman's closing control is lost after the door has begun its closing movement. 85

13. The combination with a door, a motor for opening and closing the door, an electromagnetic controller for said motor, a doorman's door opening circuit connected with 90 said controller, a doorman's door closing circuit connected with the controller, a yielding guard mounted on the door, contacts on the door operated by the movement of said guard, a doorman's controller for opening 100 and closing said circuits, a branch door-opening circuit shunting the doorman's controller and extended to said contacts, and sliding contacts in said branch circuit for maintaining electric connection with the 105 door during its opening and closing movements, the doorman's closing circuit being adapted to be bridged by said sliding contact means on the door when the latter is in its open position, and to be broken when 110 the door has moved to its closing position, whereby the doorman's closing control is lost after the door has begun its closing movement, and said sliding contacts having their connection broken when the door is in 115 its full closed position.

In witness whereof I have hereunto set my hand, before two subscribing witnesses, this 16th day of July, 1914.

JAMES F. McELROY.
